CLAIM

The ornamental design for a display screen or portion thereof with graphical user interface, as shown and described.

DESCRIPTION

FIG. 1 is a front view of a first embodiment of a display screen or portion thereof with graphical user interface in accordance with my new design;

FIG. 2 is a front view of a second embodiment of a display screen or portion thereof with graphical user interface in accordance with my new design; and,

FIG. 3 is a front view of a third embodiment of a display screen or portion thereof with graphical user interface in accordance with my new design.

The outermost rectangle depicted in broken lines illustrates the perimeter of a display screen and is not part of the claimed design. The remaining broken lines illustrate portions of the graphical user interface that are not part of the claimed design.

1 Claim, 3 Drawing Sheets
